United States Patent Office

Des. 188,898
Patented Sept. 27, 1960

188,898

BURIAL VAULT

De Loss Dhority, Greeley, Colo., assignor to Fiber
Craft, Inc., a corporation of Colorado

Filed July 30, 1959, Ser. No. 56,995

Term of patent 14 years

(Cl. D19—1)

Fig. 2

Fig. 3

Fig. 1 is an exploded perspective view of a burial vault, showing my new design;

Fig. 2 is an assembled opposite side elevational view; and

Fig. 3 is an assembled opposite end elevational view thereof.

I claim:

The ornamental design for a burial vault, as shown.
